United States Patent Office.

CHARLES N. MORGAN, OF GRANBY, MASSACHUSETTS.

Design No. 3,582, dated July 13, 1869.

DESIGN FOR A WRENCH-HEAD.

The Schedule referred to in these Letters Patent and making part of the same.

To all whom it may concern:

Be it known that I, CHARLES N. MORGAN, of Granby, in the county of Hampshire, and State of Massachusetts, have invented and produced a new and original Design or Configuration for a Wrench-Head, of which the following is a full, clear, and exact description, reference being had to the accompanying drawings, making a part of this specification, whereon like letters mark like parts, and whereof—

Figure 1 is a side elevation.

My design has no reference to the handle *d*, or that part shown in the accompanying drawings to the right of line *y-z*, but relates wholly to the head of the wrench, and more particularly to its mouth or nut-opening *a*; and the peculiarity of my design consists in making the inner or nut-face *b* of one of the jaws *c* straight, or nearly so, and providing the same with

teeth *e*, while the inner or nut-face *b'* of the other jaw *c'* pursues a circular direction, illustrated in fig. 1, the object thereof being to make the same wrench applicable to different sizes of nuts.

The outer edges *f f'* of the jaws *c c'*, I make curvilinear in form, as shown in the drawing.

I make my wrench with flat sides, and of any desirable thickness, according to the sizes of the nuts to be turned thereby.

Thus, having described my invention or production, What I claim as new, and desire to secure by Letters Patent, is—

The design for a wrench-head, herein set forth.

C. N. MORGAN.
